UNITED STATES PATENT OFFICE

EDWARD FRYSLIE, OF IOWA FALLS, IOWA

TILE CLEANING APPARATUS

Application filed September 21, 1931. Serial No. 563,974.

The object of this invention is to provide an improved apparatus and method for cleaning lines of tile or pipe for removing accumulations therefrom without disturbing the lines to any considerable extent.

Still another object of the invention is to improve and simplify the operation of cleaning pipe or tile lines and maintaining their flow capacity and efficiency.

10 Still another object of the invention is to provide an improved tool for traversing a line of pipe or tile and removing accumulations therefrom.

15 With these and other objects in view my invention consists in the construction, arrangement and combination of the various parts of my device, whereby the objects contemplated are attained, as hereinafter more fully set forth, pointed out in my claims, and 20 illustrated in the accompanying drawings, in which:—

Figure 1 is a sectional view longitudinally of a line of tile to be cleaned, illustrating two stations from which the work is carried 25 on and further illustrating at one of these stations the means for removing a tile unit so that access may be had to the line of tile.

Figure 2 is an enlarged cross section on the line 2—2 of Figure 1, illustrating particularly the grappling means for engaging and lifting a tile from the line.

Figure 3 is a similar view showing how the grappling means may be adjusted for engaging a tile of smaller diameter.

35 Figure 4 is a diagrammatic sectional view showing the means for establishing a line of communication through the pipe line whereby the cleaning tool may be reciprocated therein.

40 Figure 5 is a plan view showing two work stations which have been established in connection with a pipe line and illustrating the draft means associated with these two stations for reciprocating a cleaning member therebetween.

Figure 6 is an enlarged longitudinal section substantially on the line 6—6 of Figure 5 and illustrating the cleaning tool as it is being moved into position for starting the cleaning operation.

Figure 7 is a similar view illustrating the cleaning tool as it is moved for cleaning the pipe line.

Figure 8 is a plan view of the cleaning tool.

Figure 9 is a cross section of the cleaning tool on the line 9—9 of Figure 7.

My invention relates and is applicable to the operation of cleaning and removing accumulations of dirt and the like and roots 60 from lines of drain tile, sewer pipe and the like. It is to be understood that when expressions are used in this specification and the claims as referring to lines of pipe or tile, such expressions are to be considered 65 as inclusive of any similar lines to which my method and apparatus may be applicable.

I first establish work stations at suitable intervals along a pipe line which may be 70 composed of tile or pipe units 10. The stations are spaced apart suitable distances depending somewhat upon the size and nature of the line to be worked upon and the nature of the soil and terrain, the spacing usually being from fifty to seventy-five feet.

Two of the work stations are illustrated and are designated generally as A and B. The stations are produced by digging pits 80 in the ground over and communicating with the pipe line and framing or curbing such pits by the use of lumber or the like as indicated at 12. As indicated the curb members 12 may engage and be supported by 85 vertically arranged angular corner pieces 14.

The next step is to remove one or more of the tile or pipe units 10 at each work station and thus afford access to the remaining portions of the line from both ends thereof. This may be accomplished in any desired way, but I prefer to employ a special form of grappling and lifting device which is shown particularly in Figures 2 and 3, the 95 construction and operation of which will now be set forth.

The grappling and lifting device includes a pair of spaced arms 16 and 18 which may be made of angle or channel iron bars and 100

which are formed at their lower ends with inwardly curved portions 16' and 18'.

The curved portions 16' and 18' are adapted to engage beneath and partially embrace the unit 10 which is to be lifted.

At their upper ends the arms 16 and 18 are movably and adjustably connected by a cross bar 20 which may have its end portions extended slidably through slots in said arms. The cross bar 20 is provided near each end with a series of bolt openings 22 through which stop bolts 24 may be selectively mounted for engagement with the inner faces of the arms 16 and 18. The bolts 24 are placed in selected holes 22 to correspond in spacing to the approximate diameter of the unit 10 in order that the arms 16 and 18 may be held substantially in parallelism.

The arms 16 and 18 are also connected between their ends by a cross rod 26 which extends through openings in said arm and is threaded at its outer ends to receive nuts 28, which as shown may engage spacing washers or blocks 30. After the arms 16 and 18 have been placed about the unit 10 and the stop bolts 24 of the upper cross bar have been placed in position for properly spacing the arms, then the nuts 28 are tightened up to draw and bind the arms 16 and 18 tightly against the unit to afford a clamping engagement thereon.

The cross bar 20 is provided with an eye or the like 32 engaged by a rope or cable 34 to which lifting force may be applied by the use of a chain hoist or block and tackle, not shown, for lifting the tile unit from its place.

As indicated in Figure 1 the arms 16 and 18 may each be provided with a series of openings 36 for selective placement of the cross rod 26 so that said rod may be placed in the desired position relative to the unit 10.

It is obvious that because of the different means of adjustment of the cross bar 20 and cross rod 26, the grappling and lifting device may be employed for engaging and lifting tile or pipe units of different diameter as suggested in Figures 2 and 3.

When a unit has been removed at each of two successive work stations such as A and B access is thereby afforded to both ends of a section of the line extending between said stations.

The cleaning operation is carried out by reciprocating a special form of tool back and forth through the open section of the line by means of steel wire or cables 38 and 40 fixed to its respective ends and projecting from the section of pipe line at the respective work stations.

It is necessary to provide means for extending the draft ropes 38 and 40 through

the opened section of pipe line and this may be accomplished as indicated diagrammatically in Figure 4.

I employ a plurality of rods or bars 42 which may be connected end to end in series by the use of bolts or other securing members 44. The bars 42 may be successively connected by a workman at one of the stations, such as A, and be projected through the section of pipe line which has been opened until such time as the initial end of the series reaches the next station, such as B, after which it may be pulled through the pipe section by another workman at the latter station and carrying with it a cord or the like 46 attached to the rear end of the series. It will be obvious that the series of bars 42 need not be disassembled or removed, but may be projected into the next section extending beyond the station B. In this manner it may be employed successively at each station for carrying the cord 46 through the next successive section of pipe line to be cleaned. The cord 46 is employed for pulling after it through the pipe section one of the draft ropes such as 40.

The cleaning tool which is reciprocated through the section of pipe line by use of the cables 38 and 40 is shown particularly in Figures 8 and 9. It consists of an elongated horizontal frame work 48 having at each end a clevis 50 to which one of the ropes such as 38 and 40 may be attached. The tool also includes a centrally arranged keel bar 52 which has its major portion disposed considerably below the plane of the frame 48.

A plurality of cleaning blades 54, in this instance two in number, are pivotally mounted within the frame 48. The pivotal mounting of the blades 54 may be accomplished by means of eyes or bearings 56 thereon near their rear margins pivotally engaging cross rods 58 extending transversely of the frame.

The cleaning blades 54 normally extend downwardly and forwardly in inclined positions from their pivots and are supported loosely at their forward ends on the keel bar 52. The blades 54 preferably are formed at their forward or lower margins with notches 60 to accommodate the keel bar and to permit the lower margins of the blades to assume positions substantially in the plane of the lower edge of the keel bar.

It will be noted also that the cleaning blades 54 are curved at their lower margins and this curvature should correspond substantially with the curvature of the units 10 of the line to be cleaned.

The cables 38 and 40 which have been attached to the respective ends of the cleaning tool are projected upwardly from the respective work stations A and B and preferably through inclined openings bored or otherwise formed in the ground as indicated at 62 in Figure 5, these openings extending

from the lower portions of the work stations to the surface of the ground and permitting the ropes 38 and 40 to be drawn back and forth on inclined lines in operating the tool.

- 5 The cleaning tool 38 is first drawn rearwardly toward one of the work stations such as A by draft on the appropriate cable such as 38 as indicated in Figure 6. During such movement the tool moves freely through the
 10 section of pipe line and upon or within an accumulation such as 64 of dirt or sand in the line. The keel bar 52 acts as a sort of runner and it may travel upon the lower inner surface of the tile or pipe. During
 15 such rearward movement the pivoted cleaning blades 54 are swung upwardly so that their free edges drag upon the accumulation or deposit 64. Such upward movement of the blades is limited by stops 55 projecting inwardly from the frame 48.

When the tool has been retracted to the desired distance draft is applied to its other end by means of the cable 40 and the tool is caused to travel forwardly as indicated in
 25 Figure 7. In such movement the keel bar 52 may also travel on the lower surface of the tile or pipe but the cleaning blades 54 are automatically brought into operation because their lower free edges are caused to
 30 engage the deposited accumulation 64, portions of which will be engaged and removed by said blades.

It is obvious that by continued reciprocation of the cleaning tool the entire deposit or
 35 accumulation 64 may be removed from the section of pipe line to one of the work stations such as B from which it may be taken out by the use of buckets or other suitable implements.

40 In this way successive sections of the line may be cleaned at a minimum of time, labor and expense and the work may be accomplished efficiently without disturbing any considerable number of the units of the line.

45 As each section is cleaned its ends may be blocked off by the use of closing plates such as 66 in Figure 1 to prevent the entrance of foreign matter thereto until such time as the

cleaning operation shall have been completed and the units replaced which had previously been removed.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:—

1. A cleaning tool for pipes and the like comprising an open frame, a centrally arranged keel bar extending longitudinally of the frame and having a considerable portion projecting below the plane thereof, a cleaning blade pivoted on an axis transversely of the frame and having one margin loosely engaging the keel bar for limiting downward movement of the blade on its pivot, and stop means on the frame for limiting upward pivotal movement of the blade, said blade being curved on its free margin to correspond substantially to curvature of the pipe, the free margin of the blade being notched for the keel bar to permit close contact of the curved margin with the pipe surface.

2. A cleaning tool for pipe and the like comprising a horizontally arranged open frame, means at each end of the frame for attaching a draft appliance, a keel bar extending centrally below the frame in a longitudinal direction, and a cleaning blade hinged at one margin within and transversely of the frame, said blade being limited with respect to backward swinging movement, whereby the free margin of the blade may ride freely when the tool is moved in one direction and will be caused to engage trash in the pipe when moved in the other direction, said blade being curved at its free margin and said curved margin being notched for the keel bar to permit close contact with the pipe surface.

EDWARD FRYSLIE.
